(57) **CLAIM**

The ornamental design for a suction cup clamp assembly, as shown and described.

DESCRIPTION

FIG. 1 is perspective view of a suction cup clamp assembly showing my new design;

FIG. 2 is a top plan view thereof;

FIG. 3 is a first side elevational view thereof;

FIG. 4 is a second side elevational view thereof with the arm tilted further downward;

FIG. 5 is a third side elevational view thereof with the arm tilted even further downward; and,

FIG. 6 is an end elevational view thereof.
